UNITED STATES PATENT OFFICE

WILLIAM BUSFIELD, JR., OF PHILADELPHIA, PENNSYLVANIA, ASSIGNOR TO AMERICAN ENGINEERING COMPANY, OF PHILADELPHIA, PENNSYLVANIA, A CORPORATION OF PENNSYLVANIA

FURNACE FRONT WALL

Application filed July 16, 1927. Serial No. 206,218.

This invention relates to furnaces, and in particular to the construction of the front walls thereof.

An object of the invention is to so construct the front wall of furnaces that currents of air can be passed therethrough for the purpose of maintaining such front walls uniformly cool.

Another object of the invention is to provide a metallic front wall for furnaces, which wall is so constructed as to decrease the cost of maintenance of brickwork.

Another object is to provide a front wall for furnaces which is so constructed as to increase the efficiency of the furnace.

Another object is to provide a hollow front wall for furnaces, through which wall is adapted to pass the air used for combustion purposes, the front wall being so constructed as to increase the temperature and to reduce the pressure of the air, thereby aiding in the combustion of the fuel.

Other objects and advantages will herein-after appear.

The views of the drawings are:—

Figure 1 is a vertical transverse section through a furnace front wall constructed according to my invention, taken on the line 1—1 of Fig. 2;

Fig. 2 is a horizontal section as seen from the line 2—2 of Fig. 1;

Fig. 3 is a vertical section taken on the line 3—3 of Fig. 2;

Fig. 4 is a vertical section taken on the line 4—4 of Fig. 2;

Fig. 5 is a fragmentary vertical transverse section illustrating another form of construction taken on the line 5—5 of Fig. 6;

Fig. 6 is a fragmentary horizontal section taken on the line 6—6 of Fig. 5; and

Fig. 7 is a fragmentary elevation of the inner face of the wall shown in Figs. 5 and 6, and taken on the line 7—7 of Fig. 5.

My present invention is particularly applicable to the front walls of furnaces having mechanical stokers.

As is customary in the furnaces of this type each of the tuyères is provided with its own air supply duct.

In accordance with my invention, the

front wall of the furnace is so constructed that currents of air from the air supply ducts are caused to flow through the wall before entering the tuyères. Means are also provided for controlling the flow of air through the furnace wall.

Referring to the drawings, and especially to the form of the invention illustrated by Figs. 1 to 4, inclusive, the tuyères 10 are suitably carried, in spaced relation, on supports 11.

The front wall of the furnace extends upwardly from the upper ends of the tuyères.

In the present instance, the furnace wall is shown as being composed of a plurality of hollow castings that form an inner wall structure 12 and an outer wall structure 13.

The adjacent faces of the castings used in constructing the furnace front wall may be interlocked, as indicated at 14, Fig. 1, so as to provide a unitary structure.

The inner wall 12 is composed of alternate sections 15 and 16, the former being closed on three sides only, while the latter have four sides.

The tops of each of the sections 15 are open, and the bottoms thereof are closed, while both the top and bottom of each of the sections 16 are open.

Mounted above the wall and spaced slightly from the top of the sections 15 and 16 are hollow caps 17.

Surmounting the caps 17 are bricks 18 which form the roof of the furnace.

The sections 15 have a plurality of vertical webs formed integrally therewith. These webs are joined to the side of each section that is disposed adjacent to the interior of the furnace.

There is a central web 19 which projects above the top of the sections 15 and serves as a support for the abutting edges of adjoining caps 17.

On each side of the web 19 there are webs 20 which are made substantially the same height as the sides of the sections.

Each of the sections 16 has a central vertical web 21 that projects above the top thereof and serves as a support for the abutting edges of the adjoining caps 17.

The purpose of the webs 19 and 21 is to divide the inner wall into a plurality of separate chambers.

As shown clearly in Fig. 3, each of the caps 17 spans one-half of each of the sections 15 and 16.

The bottoms of the caps are open, so as to provide a chamber that overlies the adjoining portions of the sections 15 and 16.

On each side of the web 21 there are webs 22 having a height approximately equal to the height of the sides of the section 16.

It will be understood that the purpose of the webs 19, 20, 21 and 22 is to provide ample surfaces for radiating the heat of the inner walls of the sections 15 and 16.

Below the sections 16, and communicating therewith, are air ducts 23, formed from sheet metal.

The air ducts are disposed between alternate pairs of the supports 11.

The supports 11 are so designed as to carry the sections 15 and 16 (see Fig. 3) as well as the tuyères (see Fig. 1).

The outer wall 13 is so constructed that the portion thereof adjacent to the sections 15 is in communication therewith, while the portion thereof adjacent to the sections 16 is not in communication with the latter sections of the inner wall.

The portion of the outer wall 13 that is disposed contiguous to the sections 15 is divided by vertical webs 24, while the side of the wall abutting the sections 15 is open, as indicated at 25.

The outer wall 13 also has vertical webs 26 which have openings 27 formed therein.

The webs 24 are positioned in alignment with the webs 19 of the sections 15, and the webs 26 are disposed in alignment to the adjoining sides of the sections 15 and 16.

The construction of the outer wall 13 is such that chambers 28 communicating with the sections 15 are formed. Between these 45 chambers, there is a chamber 29.

The chambers 28 have closed bottoms, while the chamber 29 has an open bottom through which the air flows in its course to the tuyères, as indicated by the arrows 50 44 in Figs. 1-4.

The chambers 29 are disposed in the outer wall section in alignment with the tuyères, while the chambers 28, are, as shown, disposed on each side thereof and are 55 in direct communication with the portions of the sections 15 lying on each side of the section 16.

The portions of the outer wall in which the chambers 29 are formed have openings 30 which are closed by vertically swinging doors 31.

The doors 31 are adapted to be swung inwardly by suitable means including levers 32, so as to close the openings 46 in the bottom 65 of the chambers 29, and permit exit of the

air to the boiler room, as will be hereinafter more fully described.

In operation the air is conducted from the plenum chamber upwardly through the ducts 23 into the sections 16, as indicated by the 70 arrows 45 in Figs. 1-3.

The webs 21 divide the air into two parts, one of which flows past the webs 22 on the right hand side of the webs 21, while the other portion of the air flows past the webs 75 22 on the left hand side of the webs 21 (see forked arrow 47 Fig. 3).

In its passage upwardly through the sections 16, the air will absorb heat radiated 80 from the webs of the section.

From both parts of the sections 16 the air flows into the caps 17, and from here it flows downwardly through the adjacent portions of the sections 15 (see arrows 45 in Fig. 3).

The air then flows through the openings 25 into the chambers 28 and continues through the openings 27 into the chambers 29, from which it flows downwardly and forwardly, between the supports 11, to the 90 tuyères.

When the doors 31 close the openings 30, the air will circulate through the front of the furnace in the manner just described, but when the doors are swung downwardly, the 95 air will be deflected thereby and pass outwardly through the openings 30 into the furnace room.

The air passing through the sections 15 and 16, and the caps 17 reduces the temperature 100 of the front wall, and in so doing absorbs heat.

The heated air is delivered into the furnace through the tuyères 10 and aids in the combustion of the fuel, thus increasing the 105 efficiency of the furnace.

Another advantage gained by using my construction is, that due to the friction through the various passages in the front wall, the air pressure is reduced in the upper 110 portion of the fuel bed, thus preventing any tendency of the particles of fuel to blow up from the fuel and facilitating the combustion of the volatile gases in the fuel.

When the boiler is banked and air is no 115 longer required for combustion, provision must be made to keep the front wall airbacks from becoming too hot, by passing air through them.

This is the purpose of the doors 31 described above.

When the boiler is banked, the doors 31 are operated, so as to close the openings in the bottoms of the chambers 29 and allow the air to pass into the boiler room until the temperature of the furnace is low enough to prevent burning of the cast iron from which the sections 15 and 16 and the caps 17 are constructed, at which time the air supply can be 125 shut off entirely.

The advantages in the construction herein shown and described will be readily apparent when the decreased cost of maintenance of brick work in the front wall, the increased efficiency due to the increased temperature of the air used for combustion purposes, and the reduced air pressure aiding in the combustion of the fuel, are taken into consideration.

10 The embodiment shown in Figs. 5, 6 and 7 is essentially the same as that previously described but differs therefrom in that the surfaces of the inner wall that are exposed to the fire are shown as being faced with fire brick 40. The inner surfaces of the sections comprising the inner wall may be formed with vertical T-shaped ribs 41, and the bricks 40 may have grooves 42 for receiving the limbs of the ribs 41. The intervening spaces between the bricks can be filled with fire clay or other cementitious material 43.

15 The invention set forth herein is, of course, susceptible of various other modifications and adaptations.

20 The invention claimed is:—

25 1. A furnace comprising fuel-supporting tuyères, a front wall provided with vertical passages in its inner portion and vertical passages in its outer portion, the inner passages communicating at their lower ends with a source of air supply, means leading from the lower ends of the outer passages to the tuyères, and means establishing communication between the inner and outer passages.

30 2. A furnace comprising fuel-supporting tuyères, a wall provided with vertical passages both in its inner and outer portions, the inner passages being connected in sets to form tortuous passages with one terminal passage of each set connected with a source of air supply and the other terminal passage of each set communicating with one of the outer passages, and means connecting the outer passages with the tuyères.

35 3. A furnace comprising fuel-supporting tuyères, a front wall provided with vertical passages both in its inner and outer portions, the inner passages communicating with a source of air supply and being provided with 50 heat-transferring fins projecting from their rear walls, means connecting the outer passages with the tuyères, and means establishing communication between the inner and outer passages.

40 4. A furnace comprising fuel-supporting tuyères, a front wall provided with vertical passages both in its inner and outer portions, the inner passages being separated into sets of two with the passages of the respective sets communicating with each other at their upper ends, the lower end of one passage of each set being connected with a source of air supply and the lower ends of the other passages of the respective sets being connected with

the said outer passages, and means leading from the said outer passages to the tuyères.

45 5. A furnace comprising fuel-supporting tuyères, a front wall provided with passages both in its inner and outer portions, the passages in the inner portion being connected in sets to form tortuous passages, one end of each of which is connected to a source of air supply while the other end is connected with an outer wall passage, and means leading from 50 the said outer passages to the tuyères whereby air is conducted from the source of supply through the inner tortuous passages and discharged through the outer passages to the tuyères.

55 6. In a furnace, a wall comprising inner and outer hollow sections, the inner section being divided into a plurality of passages each of which is connected at one end to a source of air supply and at the other end to 80 the outer hollow section, and means establishing communication between the said outer section and the interior of the furnace.

60 7. In a furnace, a wall comprising inner and outer hollow sections each of which is 85 divided into a plurality of separate passages, each of the passages of the inner section communicating with a passage of the outer section, means for establishing communication between the passages of the outer section and the interior of the furnace, and means for directing air upwardly into the passages of the inner section and downwardly from the 90 passages of the outer section into the interior of the furnace.

65 8. In a furnace, a wall having inner and outer portions both of which are composed of contiguous hollow sections forming vertical 95 passages, means including a plurality of hollow caps overlying the said hollow sections of the inner wall portion for connecting the vertical passages of the latter in sets forming a tortuous way paralleling the inner face of the said wall, means for establishing communication between the passages of the inner and outer sections, and means for directing air into the said tortuous way formed in the inner wall portion and outwardly from the 100 passages of the outer wall portion into the interior of the furnace.

70 9. In a furnace, a wall having inner and outer hollow portions, both of said portions being divided into a plurality of independent passages, each of the passages of the inner portion communicating with a passage of the outer portion, means for connecting each of said inner passages with a source of air supply and for establishing communication between each of said outer passages and the interior of the furnace, and adjustable means for diverting air entering the outer 105 passages from the inner passages to the exterior of the furnace.

75 10. In a furnace, a wall comprising inner and outer portions, the inner portion com-

prising contiguous hollow sections one of which is open at both top and bottom while the other is open at the top only, a cap member overlying said sections and forming therewith a tortuous passage extending upwardly through the one section and downwardly through the other, said outer wall portion also comprising hollow sections, and means for establishing communication between the bottom of the last-named inner section and one of the hollow sections of the outer wall portion, the lower open end of the said inner section last-named being connected with a source of air supply and the associated hollow outer section communicating with the interior of the furnace.

11. In a furnace, a wall comprising inner and outer portions, the inner portion comprising contiguous hollow sections one of which is open at both top and bottom while the other is open at the top only, a cap member overlying said sections and forming therewith a tortuous passage extending upwardly through the one section and downwardly through the other, said outer wall portion also comprising hollow sections, means for establishing communication between the bottom of the last-named inner section and one of the hollow sections of the outer wall portion, the lower open end of the said inner section last-named being connected with a source of air supply and the associated outer section communicating with the interior of the furnace, and adjustable means for diverting air passing through said hollow sections to the exterior of the furnace.

12. In a furnace, a wall comprising inner and outer hollow portions, both of said portions being divided into a plurality of independent passages, means for establishing communication between the passages of the inner portion and the passages of the outer portion, means for connecting the passages of the inner portion with a source of air supply and the passages of the outer wall portion with the interior of the furnace, said outer passages having also ports for connecting said passages to the exterior of the furnace, doors normally closing said ports, and means for adjusting said doors to break communication between said outer passages and the interior of the furnace and to open said ports whereby air passing into the outer passages from the inner passages is discharged to the exterior of the furnace.

13. A furnace comprising fuel-supporting tuyères, a wall provided with vertical passages both in its inner and outer portions, the inner passages being connected in sets to form tortuous passages with one terminal passage of each set communicating with one of the outer passages, the other terminal passages of the said sets and the corresponding outer passages being connected one with a

source of air supply and the other with the tuyères.

14. A furnace comprising fuel-supporting tuyères, a wall provided with vertical passages both in its inner and outer portions, the inner passages being separated into sets of two with the passages of the respective sets communicating with each other at their upper ends, the lower end of one passage of each set being connected with an outer passage, and the lower ends of the other passages of said sets and the outer passages being connected one to a source of air supply and the other to the tuyères.
